UNITED STATES PATENT OFFICE.

WILLIAM G. CARSON, OF BALTIMORE, MARYLAND, ASSIGNOR, BY DIRECT AND MESNE ASSIGNMENTS, TO THE AMERICAN LAUNDRY MACHINERY COMPANY, OF CINCINNATI, OHIO, A CORPORATION OF OHIO.

WASHING MACHINE.

Application filed August 16, 1916, Serial No. 115,312. Renewed June 1, 1921. Serial No. 474,296.

To all whom it may concern:

Be it known that I, WILLIAM G. CARSON, a citizen of the United States, residing at Baltimore, in the county of Baltimore and 5 State of Maryland, have invented certain new and useful Improvements in Washing Machines, of which the following is a specification.

My invention relates to new and useful 10 improvements in washing machines.

The object of my invention is to provide a washing machine, in which the admission of steam and hot or cold water is automatically controlled, so that the proper amount 15 of steam and hot or cold water can be admitted to the washing cylinder at a predetermined time, so that the clothes can be washed, boiled and rinsed in the same cylinder.

20 Another object of my invention is to provide a washing machine having automatic means for supplying the cylinder with the necessary washing and bluing compounds, and having certain details of structure and 25 combination of parts hereinafter more fully described.

In the accompanying drawings:—

Figure 1 is a top plan view of a washing machine, showing my invention applied 30 thereto;

Figure 2 is a front elevation of Figure 1, parts being omitted;

Figure 3 is an end view of Figure 1 looking in the direction of the arrow and showing the washing compound receptacle partly broken away, parts being omitted;

Figure 4 is a perspective view of one end of the travelling carriage and a valve operating shaft;

40 Figure 5 is a perspective view of the drive worm, and showing in separated position the means of connecting and disconnecting the carriage thereto;

Figure 6 is a perspective view of the valve 45 operating means for the washing compound receptacles.

Referring now to the drawings, 1 represents the tub or cylinder of a washing machine which has secured at each end the 50 upwardly extending end frames 2 and 3 connected by the side bars 4 and 5, forming a rectangular frame resting on the upper portion of the washing cylinder and carrying the plate 5' forming a support, as herein-

after set forth. Carried by the plate 5' at 55 points adjacent the end frame 3 are three cylinders 6, 7 and 8, which are supplied with steam by means of the pipe 9, having branch pipes 10, 11 and 12 leading to the respective cylinders. Within the cylinders are arranged 60 pistons which have their piston rods 13, 14 and 15 extending outwardly beyond the ends of the cylinders and connected to the valves 16, 17 and 18 controlling the hot water, cold water and steam supply pipes 65 respectively which are connected to the washing machine cylinder at any desired point. Connected to the steam supply pipe 9 is a branch pipe 19 which leads around one side of the rectangular frame and is 70 connected to the cylinder 20 carried by the opposite end of the rectangular frame. Within this cylinder 20 is a piston having its piston rod 21 extending downwardly and connected with the valve 22 arranged within 75 the discharge pipe 23 of the washing machine cylinder. The branch pipes 10, 11, 12 and 19 are provided with valves 26, 25, 24 and 27 respectively, having valve stems 28 extending downwardly and connected to 80 cranks 29 carried by the shafts 32, 31, 30 and 33 respectively. These shafts, as shown in Figures 2 and 3 of the drawings, are mounted in the end frames 2 and 3 and are arranged in the same horizontal plane. As 85 will be readily understood these shafts are mounted in the frames, so that they may rock and cause the cranks 29 to move the valve stems 28 to admit steam to the cylinders in order to open the valves controlling 90 the hot water, cold water, steam and drain.

Carried by the shafts 32, 31, 30, and 33 are a suitable number of sleeves 34 adjustably held thereon by set screws 35 and having at 95 one side the extensions 36. These extensions have a longitudinally adjustable portion 37, the purpose of which will later appear. Mounted within the end frames 2 and 3, above said shafts, is a worm or screw 38, shown conventionally in Fig. 5 and which supports a carriage 39, which in plan view, is wider than the distance between the shafts 30 and 33, as shown in Fig. 1. The lower edge of said carriage has hinged thereto several shoes 40 free to swing in one direction, to wit, to the left in Figs. 2 and 4, and held against movement in the opposite direction. Said shoes are each provided 100

105

with a roller 41 suitably journalled therein. Each of said rollers is adapted to engage one of the extensions 36 and its adjustable portion 37 and rock one of the shafts 32, 31, 30, 5 or 33, whereby the valves of the water and steam supplies and drain are controlled. Carriage 39 is provided with a nut consisting of two pivoted jaws, 42, 43, pivoted in the carriage at their apertured ends 42^a and 10 43^a, as indicated in Figs. 1 and 5, and which jaws are operated by a lever 44. Lever 44 is provided with an eye portion 44^b surrounding screw shaft 38 and provided with two cam slots 44^a engaging pins 42^b, 43^b, to open 15 and close jaws 42, 43 upon the screw after the manner of the usual split nut. Lever 44 also has a horizontally extending arm portion 44^c which engages the inclined lower edge of a stop 50 on the stationary frame as 20 the carriage moves to the left, Fig. 2, for a purpose which will later appear.

The worm 38, on the outside of the frame 2, is provided with a worm-gear 45 meshing with the worm 46 carried by the shaft 47. 25 The shaft 47, on the outside of the rectangular frame is provided with an idle pulley 48 and a fast pulley 49 for receiving power from a belt and whereby the worm 38 is driven, as will be readily seen by reference 30 to Figure 3 of the drawings.

When it is desired to admit either hot water, cold water or steam into the washing machine cylinder the sleeve 34 of the respective shaft is adjusted thereon and as the carriage travels to the left, as shown in Figure 35 2 of the drawings, the proper roller 41 engages the extension 36 and rocks the shaft and opens the valve allowing steam to pass to the proper cylinder 6, 7, or 8, which actuates valve 16, 17, or 18 whereby either hot water, cold water or steam is admitted to the washing machine cylinder. By adjusting the extension 37 the valve is held open for a longer or shorter period of time, so as 40 to admit more or less hot water, cold water or steam to the cylinder, whichever case it may be. The same operation takes place when it is desired to discharge the contents of the washing cylinder, thus admitting 45 steam to the cylinder 20 and opening the valve 22. When the carriage reaches the stop 50 the lever 44 is engaged by the inclined face thereof and is forced downwardly to move the jaws 42 and 43 out of 50 engagement with the worm 38 and automatically stop the carriage. The carriage is then moved back by the operator to the right of the machine and the shoes 40 swing upon their pivots when they engage the extensions 36 and thus present the opening of 55 the valves, as will be readily understood.

Carried by the plate 5' is an elongated receptacle 51 divided into six compartments 52, 53, 54, 55, 56 and 57, which are adapted 60 to receive soda solution, soap solution, bleach

solution and bluing or any other compounds found necessary in the washing of clothes. Each of the receptacles is provided with a discharge pipe 58 leading downwardly and connected to the washing machine cylinder. 70 Each pipe 58 is provided with a valve 59, the valve stem of which has an arm 60 secured thereto and to the lower end of said arm 60 is pivotally connected a rod 61. This rod 61 extends parallel with the frame member 4, as shown in Fig. 1, and is pivotally connected at 62 to the upper end of an arm 63 on a rock shaft 63^a. This rock shaft 63^a turns in a portion 64^b of a sleeve 64 adjustably supported by the shaft 65 which extends 80 through the rectangular frame longitudinally thereof and parallel with the shafts 30, 31, 32 and 33, as shown in Fig. 3.

The end of each rock shaft 63^a is provided with an extension 66 which is engaged by 85 the roller of one of the shoes 40 whereby the valve of the particular washing compound receptacle is opened to supply the washing cylinder with the contents thereof. When said roller passes off from the extension 66 the valve is closed by a tension spring 60^a which extends from the arm 60 to any suitable fixed point. The sleeve 62^a at the connection between the arm 63 and the rod 61 of the arm 60 carried by the valve is 90 removable so that the operating parts can be disconnected from the valve of any one of the discharge pipes of the different washing solutions. Also by adjusting sleeves 62^a and 64 along the rod 61 and shaft 65, respectively, any one of the valves 59 may be caused 95 to open at any desired time during the traversing motion of the carriage 39 from the right to the left, in Fig. 1. The six different solutions are supplied to the washing cylinder by means of the single shaft 65, through the operation of the roller carried by the carriage passing in turn over the several extensions 66 adjacent these receptacles. The bottom of each washing solution receptacle is made slanting to facilitate the discharge of said solution from the receptacle. 100

By the above described invention, it will be seen that the supply of the steam, hot water and cold water to the washing cylinder is under perfect control of the operator and the discharge from the washing cylinder is also controlled. It will also be seen that any one of the washing compounds may be supplied automatically to the washing cylinder. By properly spacing the control devices 34 along the several shafts 32, 31, 30, 33, and the devices 64 and 62 along shaft 65 and rods 61 the machine may be made to carry out any desired cycle or formula of washing operations during a single traverse of the carriage 39 from the right to the left in Fig. 1, thereby enabling any formula involving successive treatments of the clothes with different liquids, com- 115 120 125 130

pounds, or materials to be readily repeated on successive batches of clothes. The adjustability of the parts also enables the cycle or formula to be readily changed, as desired. While I have shown this specific construction and arrangement of parts, it will be understood that the same could be varied without departing from my invention, and the automatic means for controlling the washing solutions are adapted to be applied to the shafts for operating the steam, hot water, cold water and discharge:

The stop 50 has connected thereto an electric wire 67 which leads to a bell 68 and which rings when the carriage has reached its limit of movement.

Having thus described my invention, what I claim as new and desire to secure by Letters Patent, is:

20 1. A washing machine comprising a cylinder, a frame mounted upon the cylinder, shafts mounted in the said frame, steam, hot water and cold water supply pipes for said cylinder, valves controlling said supply pipes and connected to the said shafts, and a movable carriage for rocking the shafts for opening the said valves at a predetermined time.

2. A washing machine comprising a cylinder, a frame mounted upon the cylinder, shafts mounted in the said frame and adapted to oscillate, steam, hot water and cold water supply pipes for the said cylinder, a discharge for said cylinder, valves in said supply pipes and connected for control by the rocking shafts, a worm above said shafts, a carriage on said worm, means for connecting and disconnecting the carriage to the worm, and means carried by the carriage for oscillating the several shafts, whereby either the valve of the hot water, cold water, steam or discharge pipe may be opened or all of them may be opened, as desired.

3. A washing machine comprising a cylinder, a frame mounted upon the cylinder, a plurality of shafts mounted in the frame and adapted to oscillate, a steam supply pipe for the said cylinder, a hot water supply pipe for the cylinder, a cold water supply pipe for the cylinder, piston rods connected to the valves of said supply pipes, a discharge pipe, a piston connected to the valve of said discharge pipe, fluid pressure operated means for operating said pistons, a valve for controlling each of said pistons, valve stems carried by the valves and connected to the shafts, a driven worm carried by the frame above the oscillating shafts, a carriage supported by the worm, jaws carried by the carriage and engaging the worm, a lever for causing the jaws to engage and disengage the worm, a stop carried by the frame and adapted to engage the lever to automatically disengage the carriage from the worm, shoes carried by the

lower end of the carriage, adjustable sleeves carried by the oscillating shafts and having adjustable extensions engaged by the shoes for rocking the shafts and opening the valves, a washing compound receptacle carried by the frame having several compartments to receive different washing compounds, a discharge pipe for each compartment, a valve controlling each discharge pipe, and means whereby the valve of any receptacle is opened by the longitudinal movement of the carriage.

4. A washing machine comprising a cylinder, steam and water supply pipes for said cylinder, valves controlling said supply pipes, shafts connected to control said valves, a washing compound receptacle above the cylinder and having several compartments to receive different washing compounds, a discharge pipe for each compartment, a valve controlling each discharge pipe, a driven worm, a carriage operated thereby, and means carried by the carriage for operating said shafts and operating the valves for the washing compound discharge pipes, whereby the said valves are opened at a predetermined time.

5. A washing machine, comprising a cylinder, water supply pipes therefor, controlling valves for said pipes, a drain valve for said cylinder, a plurality of sources of supply of washing compounds, controlling valves therefor, a movable controlling member, and means whereby the movement thereof controls the valves for said drain, water supply pipes, and the supplies of said washing compounds.

6. A washing machine, comprising a cylinder, water supply pipes therefor, controlling valves for said pipes, a drain valve for said cylinder, a plurality of sources of supply of washing compounds, controlling valves therefor, a movable controlling member, means whereby the movement thereof controls the valves for said supply pipes, drain and the supplies of said washing compounds, and means for adjusting the control means for said valves to vary the sequence of operation of said valves.

7. A washing machine, comprising a cylinder, water supply pipes therefor, controlling valves for said pipes, a drain valve for said cylinder, a plurality of sources of supply of washing compounds, controlling valves therefor, a reciprocating member, and means carried thereby and adapted by movement thereof to control said several valves.

8. A washing machine, comprising a cylinder, water supply pipes therefor, controlling valves for said pipes, a drain valve for said cylinders, a plurality of sources of supply of washing compounds, controlling valves therefor, a controlling member for each valve, and a movable operating member adapted by movement in one direction

to engage in turn either all or any of said members.

9. A washing machine, comprising a cylinder, water supply pipes therefor, controlling valves for said pipes, a drain valve for said cylinder, a plurality of sources of supply of washing compounds, controlling valves therefor, a controlling member for each valve, a movable operating member adapted by movement in one direction to engage in turn all or any of said members, said members being adjustable to vary the sequence of the valve operations.

10. Washing apparatus comprising a washing machine having a receptacle to receive the goods to be washed and the materials for treating the same during the washing operation, a drain valve for said receptacle, a water supply and a plurality of supplies of washing materials communicating with said receptacle, and means for automatically controlling said valve and the communication of said several supplies with said receptacle to automatically produce any desired series of washing treatments in said receptacle.

11. Washing apparatus, comprising a washing machine having a receptacle to receive the goods to be washed and the materials for treating the same during the washing operation, a drain valve for said receptacle, a water supply and a plurality of supplies of washing materials communicating with said receptacle, and means for automatically controlling said valve and the communication of said several supplies with said receptacle to automatically produce any desired series of washing treatments in said receptacle, said controlling means including adjustable parts whereby the sequence of said treatments may be varied.

12. Washing apparatus, comprising a washing machine having a receptacle to receive the goods to be washed and the materials for treating the same during the washing operation, a drain valve for said receptacle, a water supply and a plurality of supplies of washing materials communicating with said receptacle, and means for automatically controlling said valve and the communication of said several supplies with said receptacle to automatically produce any desired series of washing treatments in said receptacle, said controlling means including adjustable parts whereby the order of the several treatments may be varied.

13. Washing apparatus, comprising a washing machine having a receptacle to receive the goods to be washed and the materials for treating the same during the washing operation, a drain valve for said receptacle, a water supply and a plurality of supplies of washing materials communicating with said receptacle, and means for automatically controlling said valve and the

communication of said several supplies with said receptacle to automatically produce any desired series of washing treatments in said receptacle, said controlling means including adjustable parts whereby the duration of different treatments may be varied.

14. Washing apparatus, comprising a washing machine having a receptacle to receive the goods to be washed and the materials for treating the same during the washing operation, a drain valve for said receptacle, a water supply and a plurality of supplies of washing materials communicating with said receptacle, and means for automatically controlling said valve and the communication of said several supplies with said receptacle to automatically produce any desired series of washing treatments in said receptacle, said controlling means including adjustable parts whereby the order and duration of different treatments may be varied.

15. Washing apparatus, comprising a washing machine having a receptacle to receive the goods to be washed and the materials for treating the same during the washing operation, a drain valve for said receptacle, a water supply and a plurality of supplies of washing materials communicating with said receptacle, and a controlling member operating through a cycle of movement and adapted to control in predetermined order said valve and said several supplies.

16. Washing apparatus, comprising a washing machine having a receptacle to receive the goods to be washed and the materials for treating the same during the washing operation, a drain valve for said receptacle, a water supply and a plurality of supplies of washing materials communicating with said receptacle, a controlling member operating through a cycle of movement and adapted to control in predetermined order said valve and said several supplies, and means for stopping the movement of said control member at the conclusion of its cycle of movement.

17. Washing apparatus, comprising a washing machine having a receptacle to receive the goods to be washed and the materials for treating the same during the washing operation, a drain valve for said receptacle, a water supply and a plurality of supplies of washing materials communicating with said receptacle, a control member having different portions movable through definite paths of movement, and means carried by said portions and adapted by movement through such paths to control in predetermined manner said valve and said several supplies.

18. A washing machine, comprising a cylinder, water supply pipes for said cylinder, a drain valve, a signal device, and a control member provided with means for auto-

matically controlling said water supply and drain valve and adapted at the conclusion of its operation to cause actuation of said signal.

5 19. A washing machine comprising a cylinder, a water supply therefor, a plurality of supplies of washing compounds therefor, a valve for each of said water and compound supplies, a drain valve, a signal device, a 10 movable control member, and means whereby the movement of said control member causes actuation of said several control valves and said signal.

20. A washing machine attachment, comprising a suitable support, a reciprocating traveler thereon, means for moving said traveler in one direction, means arranged as 15 said traveler approaches the end of said

movement to indicate the conclusion of the washing operation, and means for releasing 20 said traveler from its operating means whereby it may be freely moved manually in the opposite direction.

21. A washing machine attachment, comprising a suitable support, a reciprocating traveler thereon, a drain valve actuating member, a signal device, means for advancing 25 said traveler in one direction, means whereby the advancing movement of said traveler produces operation of said signal 30 device and drain valve operating member, and means for releasing said traveler from its operating means, whereby it can be freely retracted from its advanced position.

In testimony whereof I affix my signature.
WILLIAM G. CARSON.
